J. Granville Meyers
ATTORNEY

UNITED STATES PATENT OFFICE.

WILLIAM STRAUSS, OF NEW YORK, N. Y.

VANITY AND COMPACT CASE AND THE LIKE.

Application filed February 10, 1926. Serial No. 87,277.

My invention relates to the class of containers or "cases", having hinged lids, and intended for use principally by women as portable cosmetic containers, usually called 5 "compact" or "vanity cases", or for other purposes.

A leading object of the invention is to provide a structure which permits the cases to be made with a great variety of outer 10 coverings or "finishes", of attractive and decorative appearance, and at the same time provide a hinge mechanism suitable for these containers, which is entirely concealed when the lid is closed.

15 It is necessary in most cases, for manufacturing economy and in order to provide the necessary strength and stiffness of the bottom and lid structure with a moderate weight, to make the framework, or base 20 parts of these body and lid sections, of pressed metal; and the object of the invention, more particularly stated, is to provide a foundation structure of sheet metal which is adapted for exterior covering with non- 25 metallic, flexible sheet material of various kinds, such as textile fabrics, leather, imitation leather, and other flexible sheet materials or compositions. The metal parts and the coverings are further mutually designed 30 or arranged so that in preferred examples the metal parts are entirely covered and concealed from view when the case is closed.

An important object of the invention, incidental to those just stated, is to provide 35 a structure in which the coverings or surface finishes may easily be varied, and for example, the covering fabric or other sheet material may be matched or harmonized with particular dresses or costumes, and the 40 surface finishes of different parts of the container may, moreover, be made in two or more different contrasting colors, materials or designs.

A further important object is to provide 45 a structure or arrangement of parts which admits of economically forming or shaping the cover material upon and about, and securing it to the metal bodies or bases of the respective bottom and lid, or "finishing" ring sections, by the use of suitable dies 50 or other mechanisms.

The characteristics and advantages of the invention are further sufficiently explained 55 in connection with the following detail description of the accompanying drawing, which shows one representative embodiment

of the invention. After considering this example, skilled persons will understand that many variations may be made, and I contemplate the employment of any structures that are properly within the scope 60 of the appended claims.

In the drawings:

Fig. 1 is a front elevation of a case embodying the invention in one form, with the 65 lid open, and with some parts in section.

Fig. 2 is a vertical section, enlarged, at 2-2, Fig. 1.

Fig. 3 is a side elevation, with the lid closed, and with some parts broken away 70 or sectioned.

Fig. 4 shows certain of the metal lid parts ready for assembly.

Fig. 5 shows certain of the bottom parts and also a "finishing" ring, ready for covering and assembly. 75

Fig. 6 is a fragmentary detail, in section, of a modified construction.

Fig. 7 is a sectional view of another modification. 80

The metal frame or body of the container, as here specifically embodied in a "compact" case, comprises the bottom base member 1 and the lid base member 2, each of which is formed from a sheet metal disc pressed in 85 shallow dished form. The bottom member has a peripheral shallow lip 3 joined to the main portion by a fillet or rounded formation, and having a substantially conical contour. The lid member 2 has a similar 90 rim or lip 4. Each of these main members is covered with suitable flexible sheet material, 5 and 6 respectively. Specifically, as shown, this is woven fabric of any desired color and decorative characteristics, but 95 otherwise may be leather, imitation leather, or other suitable sheet material, usually non-metallic. The cover material is cut in circular form, and by the use of suitable dies and mechanism is smoothly bent and formed 100 over the main and outer rim contours of the body portions 1 and 2, and around the edges of the rims, and overlapped on the inner faces of the rims. There may be one or more layers of cover material. In the present example, the outer layers 5 and 6, which determine the outer finish and appearance 105 of the container, are superposed upon inner layers or sheets 7 and 8, respectively, which may be in the nature of padding or lining 110 materials, such as cotton fabric of the desired thickness, softness and texture, or other suit-

able material. The single or double covering material is arranged on a suitable die, the formed metal shell or body is placed upon it, and an upper die then acts upon the shell and the material to form it smoothly over the broad face of the shell and turn it over the outer surface and edge of the lip and lap it upon the inner face of the lip, ready for retention either by an inner retaining member or "form" 10 or an outer or "finishing" ring 25, referred to below. When a covered finishing ring is used the single or double covering material is applied to it by similar die operations and the retainer 10 and the partly covered finishing ring 25 are placed in the upper die, and by co-operation of the dies the folding or forming of the covering material about the finishing ring and about the edge and upon the inner surface of the shell lip 3, is properly completed, and finally, when the parts are forced to the final position of Fig. 2, the inturned margin of the cover materials 4 or 5 is retained by the lip 15 of the retainer 10 and also by inner lip of the finishing ring, and at the same time the inner margin of the cover fabric or fabrics folded about the inner edge of the covered bottom section. The operation of covering the lid section 30 is similar, except that it is not necessary in this case to employ a finishing ring, and the overlapped cover material is retained by the conical rim or lip 21 of a plate 20 (referred to below), which is sprung into position by the dies and then firmly holds the material, as clearly shown in Fig. 2.

The bottom cover material is secured in position by a retainer or inner box form 10, which is preferably, as shown in the general form of a sheet-metal, stepped annulus, including concentric cylindrical portions 11 and 12 joined by a flat annular web 13. The outer part of the cylinder 12 is continued to form an approximately conical outer wall 14 terminating with a curve or fillet and a lip 15, which is normally in the form of a shallow cylinder, or slightly conical. After the metal bottom member 1 has been covered in any of the ways described, the cover is secured by forcing the compact form into position, as shown in Fig. 2, whereupon the lip 15 yields inward and then resiliently presses outward against the in-turned edge or edges of the respective cover materials, and holds these edges or margins against the inner contour of the lip 3.

The lid cover material is retained by a sheet metal disc 20 which has a conical periphery 21. This disc may serve also, as later explained, as a mirror base, and a hinge-connecting or supporting member. The disc is sprung into position as shown in Fig. 2, whereupon the marginal part of the rim 21 engages the inturned margins of the single or double cover material and holds

these margins and the entire cover firmly and smoothly in position on the metal body member 2.

When desired, a finishing ring in the general form of a concave annulus 25 of pressed sheet metal, may be applied about the periphery of the covered bottom section 1. This finishing ring may be covered or uncovered. As shown in Figs. 2 and 6, this ring has an outer portion 26 in the form of a slightly convex cylinder, an approximately flat upper portion or web 27, and inward thereof, an incurved lip 28. When uncovered, the finishing ring is sprung into position, as shown in Fig. 6, with the outer nearly cylindrical portion overlying the periphery of the covered bottom section 1, and with the lip 28 overlying the periphery of the covered rim 3, and inwardly overlapping the covering material thereon, and also in engagement with the outer wall portion 14^a of the compact form 10.

As shown in Fig. 2, this finishing ring may be covered in any of the ways described, with relation to the bottom and lid members 1 and 2, that is, either with a single layer or cover material 30, or a double layer consisting of the outer or finishing layer 20 and an inner lining or padding layer 31, these flexible cover sheets being applied, formed and overlapped about the metal ring in a manner clearly explained by the drawing.

The outer or finishing cover materials, such as 5 and 6 of the bottom member and lid respectively, may be made of either similar or contrasting materials, to produce different desirable decorative effects or to harmonize with or match different dresses or costumes. When the outer finishing ring 25 is covered, this covering material may be the same as, or in harmony with, the outer cover of either body or lid section or both of them, or it may be still another contrasting color or of a different material, to produce different desirable decorative effects. When the finishing ring 25 is uncovered, as in Fig. 6, it produces a different contrasting effect, since it is of polished or otherwise finished metal of gold, silver or other desired metallic color, in contrast with the (usually) non-metallic appearance of the cover sheets 5 and 6.

Fig. 7 shows that the outer or finishing ring may be dispensed with if desired, without necessary modification of other parts of the structure.

It is important, as stated early above, in connection with other features of the invention, to provide a suitable hinge which will permit the proper, easy and full opening of the lid, to or beyond substantially upright position, as shown in Figs. 1 and 2, and will also permit easy and quick closing of the lid and proper centered location of it

in relation to the body or bottom portion 1, and which will furthermore be entirely concealed from view when the container is closed, so that the entire outer finish will 5 consist of the cover sheets, such as 5 and 6, or sometimes including the covered or uncovered finishing ring. In other words, the exterior of the closed container presents a smooth, unbroken contour, and the hinge is 10 entirely concealed from view.

To this end, in the present specific example, a slot 40 is cut in the walls 12 and 14 of the compact form, and the eye 41 of a hinge strip 42 of flat shell metal is inserted in this slot and pivotally secured by a pin 43, which extends at each end between the walls 13 and 14 against their connecting integral rounded formation 12a, and may, if necessary or desirable, be secured in any 20 suitable way, as by soldering. The hinge strip rests in a shallow guide channel 44 formed by pressing operations upon the locking disc 20 above referred to, and is slidably retained by a plate 46 secured to 25 the inner face of the disc in any convenient way, as later referred to. The holding plate 46 in the present example, serves also as a mirror frame or base, as also later explained, but otherwise it may be provided in suitable form merely for retaining the hinge strip. The end of the strip opposite the eye is formed into a hook 47 which passes through a slot 48 in disc 20, and by engagement with the lower edge 49 of this slot 30 limits the outward sliding movement of the entire lid structure with relation to the hinge strip.

When the lid is opened the hinge strip pivots by means of its eye on the pin 43 in an obvious way, and at the same time by contact of the lid structure with the adjacent portion of the bottom structure or of the finishing ring 25, the disc 20 and the holding plate are caused to slide outward 45 upon the hinge strip, so that free opening of the lid is obtained without any strain upon the parts.

The lid may be raised to right-angular position in relation to the bottom, as shown 50 in Fig. 2, or moved even farther, until stopped by engagement of hook 47 with edge 49 of slot 48. This arrangement provides, not merely for full opening of the lid, to give proper use of the mirror usually 55 fixed therein, but permits easy return of the lid structure toward the hinge eye in an obvious way, as the lid is closed, and this in turn provides for the proper centered location of the lid and partial telescoping into 60 the bottom 1 as it reaches closed position, and also for the proper entry of inner lid parts and especially the mirror, into proper portions of the bottom structure, and especially the upper cylindrical portion 12 of the 65 compact form. The described arrangement

also provides for complete concealment of the hinge structure when the lid is closed, in a way which is obvious from the drawing, without detailed explanation.

A mirror is desirably secured to the inner face of the lid structure, and this may be done in any convenient way. In the present specific example, the plate 46 above referred to, which acts as a hinge strip retainer, is also arranged as a mirror base and for that purpose has a cylindrical lip 50 to embrace the periphery of a mirror glass 51, which is retained by a ring or bezel 52. The mirror or its base 46 may be secured to locking disc 20 in any known or suitable way. In the 70 present example, disc 20 has a corresponding plurality of prongs 56, correspondingly spaced, which are inserted in the holes and clinched at the opposite face of disc 20.

When the lid is closed, the mirror is accommodated in the outer or cylindrical portion 12 of the compact form or ring, and is easily guided to its proper location therein by the sliding hinge action above referred to.

A compact and powder pad, or other desirable toilet accessories, may be placed in the lower or inner compartment, defined by the cylindrical portion 11 of retainer 10, against the inner face of the body shell 1. These cosmetics or appliances are usually 95 removable and are omitted in the drawings for the sake of illustrative clearness.

While I have illustrated and described the invention as here specifically embodied in a case for compacts or similar toilet materials and appurtenances, it is to be understood that the invention is not limited to such uses, nor is the general shape or outline of the container limited to a circular or oval form. The principles of the invention 100 as here explained may be adapted to containers intended for other purposes and which have generally oblong or other shapes, and in such cases the general form or outline of the bottom and cover bodies, and the retainers, such as 10 and 20, will be modified 105 accordingly. Evidently therefore, it is not essential that these parts shall be annular or circular, as above described for substantially round containers.

I claim:

1. A container comprising a bottom portion and a lid portion hingedly connected, each of said portions including a dished sheet body of substantial stiffness covered with a 120 different flexible sheet material overlapping the edge of the body, the stated parts being so constructed and arranged that when the lid is closed, the hinge structure is enclosed and concealed, and the entire visible surface 125 of the container consists of said cover material.

2. A container comprising a bottom section and a lid section, each including a body of stiff sheet material in dished form with 130

a peripheral lip, and a cover of flexible sheet material different from the body, overlying the exterior surfaces of the body and lip and overlapped about the edge of the lip 5 and upon the inner face thereof, and a retainer of sheet material of substantial stiffness inserted in the body and holding the in-turned margin of the cover material against the inner face of the lip, and a hinge connection between the body and lid sections.

3. A case or container comprising a bottom section and a lid section, each including a body of stiff sheet material in dished form with a peripheral lip, and a cover of 15 flexible sheet material different from the body, overlying the exterior surface of the body and lip and overlapped about the edge of the lip and upon the inner face thereof, and a retainer of sheet material of 20 substantial stiffness inserted in the body and holding the in-turned margin of the cover material against the inner face of the lip, and a hinge connection between the body and lid sections and arranged to be 25 entirely concealed when the lid is closed, and also arranged by sliding action to permit full opening of the lid and full closing thereof in centered relation to the bottom section.

4. A vanity or compact case comprising a 30 bottom section and a lid section, each including a body of stiff sheet material in dished form with a peripheral lip, and a cover of flexible sheet material different from the body, overlying the exterior surface 35 of the body and lip and overlapped about the edge of the lip and upon the inner face thereof, and a retainer of sheet material of substantial stiffness inserted in the body and holding the in-turned margin of 40 the cover material against the inner face of the lip, and a hinge connection between the body and lid sections and arranged to be entirely concealed when the lid is closed, the bottom section retainer being of substantially 45 stepped formation to provide an inner compact or puff compartment.

5. A vanity or compact case comprising a bottom section and a lid section, each including a body of stiff sheet material in 50 dished form with a peripheral lip, and a cover of flexible sheet material different from the body, overlying the exterior surface of the body and lip and overlapped about the edge of the lip and upon the inner 55 face thereof, and an annular retainer of sheet material of substantial stiffness inserted in the body and holding the in-turned margin of the cover material against the inner face of the lip, a hinge connection between the body and lid sections and arranged to be entirely concealed when the lid is closed, and a mirror secured to the inner 60 face of the lid structure.

6. A vanity or compact case comprising a 65 bottom section and a lid section, each includ-

ing a body of stiff sheet material in dished form with a peripheral lip, and a cover of flexible sheet material different from the body, overlying the exterior surface of the body and lip and overlapped about the edge 70 of the lip and upon the inner face thereof, and an annular retainer of sheet material of substantial stiffness inserted in the body and holding the in-turned margin of the cover material against the inner face of the 75 lip, and a hinge connection between the body and lid sections and arranged to be entirely concealed when the lid is closed, the bottom section retainer being of substantially stepped formation to provide an inner 80 compact or puff compartment, and a mirror secured to the inner face of the lid structure and protruding therefrom and accommodated within an outer portion of the stepped bottom section retainer.

7. A container of the class described, comprising a bottom portion and a lid portion connected, each of said portions including a dished sheet body of substantial stiffness covered with a different flexible sheet material overlapping the edge of the body, the stated parts being so constructed and arranged that when the lid is closed, the hinge structure is enclosed and concealed, and the entire visible surface of the container 90 consists of said cover material, and a finishing ring of sheet material in generally annular, dished formation and of substantial stiffness, overlapping the edge and peripheral portions of the bottom portion.

8. A container of the class described, comprising a bottom portion and a lid portion connected, each of said portions including a dished sheet body of substantial stiffness covered with a different flexible sheet material overlapping the edge of the body, the stated parts being so constructed and arranged that when the lid is closed, the hinge structure is enclosed and concealed, and the entire visible surface of the container 95 consists of said cover material, and a finishing ring of sheet material in generally annular, dished formation and of substantial stiffness, overlying the edge and peripheral portions of the bottom portion, said finishing ring 105 being externally covered with a different flexible sheet material which overlaps its edges.

9. A container of the class described, comprising a bottom portion and a lid portion 110 hingedly connected thereto, each of said portions including a dished sheet metal body of substantial stiffness covered with a fibrous sheet material overlapping the edge of the body, the stated parts being so constructed and arranged that when the lid is closed, the hinge structure is enclosed and concealed, and the entire visible surface of the container 115 consists of said cover material.

10. A container or case comprising a bot-

tom section and a lid section, each including a body of sheet metal in dished form with a peripheral lip, and a cover of fabric overlying the exterior surface of the body and lip and overlapped about the edge of the lip and upon the inner surface thereof, and a retainer of sheet material of substantial stiffness inserted in the body and holding the inturned margin of the cover material against the inner surface of the lip, and a hinge connection between the body and the lid sections.

11. A container of the class described, comprising a bottom portion and a lid portion hingedly connected thereto, each of said portions including a dished sheet metal body of substantial stiffness covered with a different flexible sheet material overlapping the edge of the body, the stated parts being so constructed and arranged that when the lid is closed, the hinge structure is enclosed and concealed and the entire visible surface of the container consists of said cover material, and a finishing ring of sheet metal in generally annular dished formation and of substantial stiffness, overlying the edge and peripheral portion of the bottom section.

12. A container of the class described, comprising a bottom portion and a lid portion hingedly connected thereto, each of said portions including a dished sheet metal body of substantial stiffness covered with a different flexible sheet material overlapping the edge of the body, the stated parts being so constructed and arranged that when the lid is closed, the hinge structure is enclosed and concealed and the entire visible surface of the container consists of said cover material, and a finishing ring of sheet metal in generally annular dished formation and of substantial stiffness, overlying the edge and peripheral portion of the bottom section, said finishing ring being externally covered with a flexible sheet material which overlaps its edges.

13. A vanity or compact case comprising a bottom base and a lid base, each of sheet metal in dished formation and covered with a different flexible sheet material, and for each said base an annular inner retainer for the cover material, a hinge strip pivotally connected to the bottom retainer and slidably fitting in a guide in the lid retainer, the lid retainer and the hinge strip having co-operating stop means, the described structure and arrangement being such that when the lid is opened the hinge strip slides in relation to the lid retainer to permit full

opening, and when the lid is closed the sliding movement of the hinge is reversed to permit full closing and partial telescoping of the lid structure in relation to the bottom structure.

14. A vanity or compact case comprising a bottom base and a lid base, each of sheet metal in dished formation and covered with a different flexible sheet material, and for each said base an annular inner retainer for the cover material, a hinge strip pivotally connected to the bottom retainer and slidably fitting in a guide in the lid retainer, the lid retainer and the hinge strip having co-operating stop means, the described structure and arrangement being such that when the lid is opened the hinge strip slides in relation to the lid retainer to permit full opening, and when the lid is closed the sliding movement of the hinge is reversed to permit full closing and partial telescoping of the lid structure in relation to the bottom structure, the hinge structure being entirely enclosed and concealed when the lid is closed.

15. A container comprising a bottom section and a lid section, each including a body of stiff sheet material in dished form with a peripheral lip, and a cover of flexible sheet material different from the body, overlying the exterior surface of the body and lip and overlapped about the edge of the lip and upon the inner face thereof, and a retainer of sheet material of substantial stiffness inserted in the body and holding the inturned margin of the cover material against the inner face of the lip, and a hinge connection between the body and lid section and arranged to be entirely concealed when the lid is closed.

16. A container or case comprising a bottom section and a lid section, each including a body of sheet metal in dished form with a peripheral lip, and a cover of fabric overlying the exterior surface of the body and lip and overlapped about the edge of the lip and upon the inner surface thereof, and a retainer of sheet material of substantial stiffness inserted in the body and holding the inturned margin of the cover material against the inner surface of the lip, and a hinge connection between the body and lid sections and arranged to be entirely concealed when the lid is closed.

Signed at New York city, in the county of New York and State of New York this 3rd day of February A. D. 1926.

WILLIAM STRAUSS.
